UNITED STATES PATENT OFFICE.

ARTHUR H. NOBLE, OF PAWTUCKET, RHODE ISLAND, ASSIGNOR TO THEODORE W. FOSTER & BROTHER COMPANY, OF PROVIDENCE, RHODE ISLAND.

LIP-STICK HOLDER.

Application filed December 10, 1926. Serial No. 153,814.

This invention relates to certain new and useful improvements in lip stick holders, and the primary object thereof is to provide novel means, which can be easily and quickly operated, for effecting movement of the lip stick into and out of the holder, and for also reliably retaining the lip stick within the holder, so as to prevent accidental movement thereof when the holder is being carried or is not in use.

The invention still further aims to provide means of the character mentioned which is of simple and economical construction and which does not detract from the appearance of the usual tubular or cylindrical holder.

In the drawings—

Fig. 1 is an elevation of the holder in closed position of the parts;

Fig. 2 is a section on line 2—2 of Fig. 1;

Fig. 3 is a view of the holder in partly open position; and

Fig. 4 is a section on line 4—4 of Fig. 1.

In proceeding in accordance with the present invention, a tubular or cylindrical holder 1 is employed which latter is provided at its bottom end with a fixed cap 2, the cap 2 having its rim slotted as indicated at 3. A thimble or socket 4 for the lip stick L is slidably mounted in the holder body 1 and has an inwardly extending seat 5 to firmly grip the lip stick. The bottom of the thimble is slotted to receive the arms of a loop 6, and the ends of the loop are bent at an angle as indicated at 7 so as to clinch the loop to the thimble 4. A cap 8 is provided for the upper open end of the body 1 and is slidable thereon and is formed with an arm 9 preferably integral with the cap. The lower end of the arm 9 is turned inwardly at right angles as indicated at 10 and is formed with a perforated knuckle 11 which latter receives the loop 6 in its perforation, thereby to hingedly or pivotally connect the arm 9 to the thimble 4.

As depicted in Figs. 1 and 2 of the drawings the parts are in housed or closed position, and in order to project the lip stick from the body for use, the cap 8 is slid outwardly carrying with it its arm 9, until the cap is free of the body, whereupon the arm 9 is swung downwardly and indicated in Fig.

ure 3 and is forced inwardly through the slot 3 and the corresponding slot 12 of the body 1 thereby projecting the lip stick from the holder. Obviously the lip stick can be projected to any desired degree by merely moving the arm 9 inwardly of the body, and employing one of the end walls of the slot 12 as a fulcrum point on which the arm swings, the arm thus having a combined sliding and swinging movement. In order to restrict movement of the thimble toward the outer end of the body 1, the arm 9 is formed with stops 14 which engage the cap 2 and restrict movement of the thimble 4 accordingly.

It will be seen that the arm 9, when the parts are in closed position, conforms to and lies flat against the body thus not detracting from the usual appearance of cylindrical lip stick holders, and at the same time providing a compact arrangement.

It will be further seen, that in operation of the carrier, the arm 9, has a combined swinging and sliding movement being guided by the end walls of the slots 12, and 3, which slots are relatively short so as to afford such movement.

Having thus described my invention what I claim as new and desire to secure by Letters Patent is:—

1. In a lip stick holder, a slotted body having a slotted closure on one end thereof which slots register, a lip stick carrier slidable in the body, a closure slidable on the opposite end of the body and having an arm formed with stops, said arm being slidable in said slots and having a right angular end received in the slots, a knuckle on the said end of the arm, and a loop on the carrier pivotally engaged with the knuckle.

2. In a lip stick holder, a slotted body having a slotted closure on one end thereof which slots register, a lip stick carrier slidable in the body, a closure slidable on the opposite end of the body and having an arm formed with a stop, said arm being slidable in said slots, and means to hingedly connect the arm to the carrier.

In testimony whereof I have signed my name to this specification.

ARTHUR H. NOBLE.
